UNITED STATES PATENT OFFICE

HENRY KIELBERG, OF MARTINS FERRY, OHIO, ASSIGNOR TO WHEELING STEEL CORPORATION, OF WHEELING, WEST VIRGINIA, A CORPORATION OF DELAWARE

SHEET METAL PACKAGE

Application filed September 28, 1929. Serial No. 395,884.

This invention relates broadly to shipping drums, and it has for its primary object to provide a sheet metal package, designed particularly as a container for nested joints of 5 stove pipe, wherein the joints are maintained in their nested relation and adequately protected against distortion during shipment and while in storage.

A further object of the invention is to provide a package of the character mentioned having an end closure and provided with means whereby said closure may be ruptured to the extent that the latter is rendered readily removable.

15 In describing the invention in detail, reference is herein had to the accompanying drawings, in which—

Figure 1 is a partial side elevation of my sheet metal package as it appears prior to 20 turning the retaining band into attaching relation to the end closure;

Figure 2 is an enlarged section on line 2—2, Fig. 1;

Figure 3 is a section similar to Fig. 2, showing the end closure in attached position; and—

Figure 4 is a partial side elevation of the package with the closure partially ruptured and illustrating the means employed in effecting its removal.

Referring to said drawings, 1 designates a cylindrical container body of a single piece of sheet metal, and 2 indicates a head, or end closure, having an upright annular flange 3. Said closure is fitted within an open end of the container body 1 in a position in which its flange 3 is closely embraced by the terminal edge of said end, as shown in Figs. 2 and 3.

For securing said closure against outward movement from its said position, a ring or band 4 of sheet metal, preferably formed of soft iron or unannealed steel, is disposed in embracing relation to the said open end of the body 1 with its upper edge portion extending outwardly an appropriate distance beyond said end, as shown in Fig. 2. Said band is secured in attached relation to said body by the simultaneous formation in said band and said body, as by means of beading

rollers, of one or more coinciding annular beads 5 and 6.

Following the mounting of the band 4, as above described, the projecting upper edge portion of said band is turned inward into seated relation to the interior surface of the closure flange 3, as shown in Fig. 3.

Introduced between the band 4 and the body 1 at one side of the latter is a narrow sheet metal strap 7 which has its upper end bent to form a hook 8 which is engaged with the edge of the open end of the body 1 and with the flange of the closure, as shown in Figs. 2 and 3. This strap, which, prior to applying the band 4, is mounted against the side of the container body with its hook in place, as above described. Said strap has such length that its lower end extends beyond the lower edge of said band to constitute a tongue 9 which is adapted to be grasped, as when the end closure 2 is to be removed, for effecting such tearing of the band as is required to release said closure.

The projecting tongue 9 is preferably disposed in conforming relation to the outer surface of the lower edge portion of the band 4, as shown in Fig. 3, but may occupy any other appropriate position. When access to the interior of the container is desired, the tongue 9 is suitably grasped and is pulled upward toward the end of said body to effect cross-tearing of the soft metal band, as indicated in Fig. 4, such tearing being continued until said band is completely severed, following which said band may readily be removed.

What is claimed is—

1. In a sheet metal package, a cylindrical body having an open end, a sheet metal band attached in embracing relation to said body at said end, a closure having an annular outwardly extending flange fitted within the embrace of said end, said band having its upper edge portion turned inwardly into interiorly seated relation to said closure flange, and a sheet metal strap interposed between said body and said band, said strap having one end anchored to said closure flange and its other end protruding from beneath the lower edge of said band to form a tongue, said

tongue being adapted to be grasped and pulled to effect cross-tearing of said band.

2. In a sheet metal package, a cylindrical body having an open end, a sheet metal band attached in embracing relation to said body at said end, a closure having an annular outwardly extending flange, said closure being adapted for fitting within said open end of said body with its flange embraced by said end, said band having its upper edge portion projecting beyond said open end and adapted to be turned into interiorly seated relation to said closure flange, and a sheet metal strap interposed between said body and said band and having an end protruding from beneath the lower edge of said band to form a free tongue and having its opposite end turned into embracing relation to the closure flange, said strap being adapted to be pulled for cross-tearing said band.

3. In a sheet metal package of the character described, a tubular body having an open end, a soft metal band disposed in embracing relation to said body at said end and having its upper edge portion projecting beyond the said end of the body, said band and said body being attached together through the provision therein of annular crimps, or beads, a closure having an outwardly extending annular flange adapted to be fitted within the embrace of said end, said projecting edge portion of the band being adapted to be turned inward into securing relation to said closure flange, and a narrow sheet metal strap disposed crosswise of said band intermediate the latter and said body, said strap having one end turned into embracing relation to the closure flange and its opposite end protruding from beneath the opposite edge of said band to form a tongue, said tongue being adapted to be pulled to effect cross-tearing of said band.

In testimony whereof, I affix my signature.

HENRY KIELBERG.
